UNITED STATES PATENT OFFICE.

BENJAMIN D. GOLDBERG, OF BROOKLYN, NEW YORK.

CARDING BRUSH.

Application filed April 19, 1924. Serial No. 707,585.

To all whom it may concern:

Be it known that I, BENJAMIN D. GOLDBERG, a citizen of the United States, and a resident of Brooklyn, in the county of Kings and State of New York, have invented certain new and useful Improvements in Carding Brushes, of which the following is a specification.

My invention relates to a hand carding device for brushing or stripping wool, cloth, furs, hair, or other fibrous materials by means of closely assembled teeth or points of wire or other material set in a suitable support.

The invention relates more particularly to a device of this general character wherein a handle is provided for operating the device, said handle being secured to the mounting which carries the brush.

The object of my invention generally stated is to provide for ready renewal of the portion of the device in which the teeth or points are embodied when said teeth become broken or bent sufficiently to affect the utility of the device and without discarding the handle and base or frame in which the card is mounted.

A further object of my invention is to provide a device of the general character just stated which shall be simple and durable in construction and in which the parts shall all be secured together so firmly that they will not become loosened during use.

Generally stated my improved construction embraces a foundation sheet of rubber, leather or other material in which the teeth are fixed or set in the usual manner, a suitable metal backing plate to which said foundation is secured and a suitable handle carrying base or support on to which the backing plate may be slid and retained by the base and by co-operation of the handle which is removably secured to the base and in attached position engages the backing to prevent it from sliding off of the base.

The invention consists in the combinations of parts and the details of construction as hereinafter more particularly stated and claimed whereby the general objects of the invention are secured.

In the accompanying drawings:

Fig. 1 is a perspective view of the rubber, leather or other foundation carrying the teeth.

Fig. 2 is a perspective view of the backing to which said foundation is secured.

Fig. 3 shows in perspective the foundation and the metal backing plate assembled and secured together.

Fig. 4 is a perspective view of the reverse 60 side of the backing plate.

Fig. 5 is a perspective view of the base showing the part by which the handle is attached thereto.

Fig. 6 is a perspective view of the reverse 65 side of the base with the handle attached and with the wire foundation and backing plate in position therein.

Fig. 7 is a perspective view of the handle detached.

Fig. 8 is a perspective view showing the foundation secured to the backing plate by the turned-over edge of the latter.

Fig. 9 is a perspective view showing the backing entered part way into the guides in 75 the base preparatory to the attachment of the handle whereby when fully entered said base is secured into position.

A leather, rubber or other foundation, usually of flexible material, in which the 80 teeth or points of the card are set is indicated at 1. At 2 is shown a backing plate of sheet metal to which the foundation is secured by means of the tongues or points 3 which are struck up and integral with the 85 metal of the plate and are adapted to be entered through slots in the foundation and to be turned down upon the same as shown in Fig. 3 to secure the foundation and its backing plate together. Instead of using teeth 90 or points as shown in Fig. 2 the foundation may be secured to the backing plate by turning over a flanged edge of said backing plate on to the upper surface of the foundation and as shown in Fig. 8.

Along one edge of the plate 2 a flange 4 having an overhang 5 may be provided, said flange and overhang being integral with the body of the plate. The overhang 5 laps over the edge of the foundation and assists 100 in holding the same down upon the plate-backing 2. Also, and for a purpose to be presently described, there may be provided an ear 6 also struck up and integral with the plate and one or more overhanging ears or lugs 7 likewise struck up from the body of the plate as more clearly shown in Fig. 4. The lugs 7 lock over the lower side of the base as will be presently described and aid in securing the base and backing firmly together. The ear 6 is formed with an eye or opening through which the threaded stud or

projection 8 carried by and projecting from the edge of the base may project when the backing carrying the assemblage of teeth or points is slid into place on the base edge-wise as will be presently described.

The handle 9 has a socket 10 in its end threaded for co-operation with the threaded stud 8. The base carrying said stud is indicated at 11. The latter may consist of 10 a plate or frame having overhanging edges or flanges 12 on its sides. These overhanging edges 12 serve to hold the plate or backing 2 down upon the base 11 when said plate is slid under the side edge then operating 15 as guides, and into position where its entering end will be locked under the rear flanged side 12. When the base is slid home into such position the lugs 7 will lock under the base and assist in holding the plate and 20 base firmly together. When the handle is screwed home upon the stud 8 its end will engage the face of the lug 6 and thus prevent withdrawal of the backing carrying the assemblage of teeth or points from the base. 25 In case it is desired to renew the points or teeth the handle 9 is removed so that the plate or backing 2 carrying the assemblage of points may be slid out from position where its edges lie under the overhang 12, the 30 eye 6 being at such time free to move over the threaded stud or pin 8 until it is freed from the same and until the side edges of the backing 11 are fully disengaged from the overhang 12.

35 Additional means for firmly anchoring the handle after it is screwed home upon the stud 8 may be provided by the lugs 13 which project from the edge of the base 11 into position to embrace the sides of the end of 40 the handle 9.

What I claim as my invention is:—

1. In a device of the character described, the combination of a foundation having the points set in it, a metal backing plate to 45 which the foundation is secured, a base and a handle attachable and detachable therefrom and engaging and locking the backing plate against movement on the base when the handle is in attached position.
- 50 2. In a device of the character described, the combination of a foundation in which the points are set, a backing plate to the face of which said foundation is secured, an ear projecting from one edge of said plate, a base having a threaded stud or stem and a handle threaded for co-operation with said stud and adapted to engage the ear when screwed home.
- 55 3. In a device of the character described, 60 the combination with a point carrying foun-

dation of a metal backing plate to the face of which the foundation is secured, a base plate and lugs upon the backing plate adapted to lock over one face of the base plate when the backing plate is slid into position 65 thereon.

4. In a device of the character described, the combination of a base, a backing for the points attachable and detachable from said base, a threaded lug or stem projecting 70 from one edge of the base, a handle attachable and detachable from the base, and a lug projecting from the base and engaging the side of the handle when screwed home as and for the purpose described. 75

5. In a carding device, the combination with a foundation sheet in which the points are set and a backing plate having tongues or points struck up out of the metal of the plate and adapted to enter through slots 80 in the foundation and to be locked down upon the same, ears or lugs also struck up from the metal of the plate near one edge thereof and a base with which the latter lugs interengage to hold the backing plate 85 down upon the same.

6. In a device of the character described, the combination of a foundation having points set therein, a backing plate or support to which the foundation is secured, a 90 base having means for attachment of the backing plate and a handle attachable and detachable from the base and adapted to lock the plate in position on the base when the handle is in attached position. 95

7. In a device of the character described, the combination with a foundation having teeth or points set in it of a backing plate and fastening means integral with said plate for securing the foundation and plate together. 100

8. In a device of the character described, the combination with a foundation having teeth or points set in it of a backing plate and fastening means integral with said plate for securing the foundation and plate together, said plate being also provided with lugs for securing the plate to a mounting. 105

9. In a device of the character described, the combination with a foundation having teeth or points set in it of a backing plate and fastening means integral with said plate for securing the foundation and plate together, said plate being also provided with a perforated ear. 110

Signed at New York, in the county of New York and State of New York, this 17th day of April, A. D. 1924.

BENJAMIN D. GOLDBERG.
